CLAIM

What is claimed is the ornamental design for a collapsible canopy, as shown and described.

DESCRIPTION

FIG. 1 is a perspective view of a collapsible canopy, illustrated in an extended position, showing the new design;

FIG. 2 is a front elevational view thereof, illustrated in the extended position;

FIG. 3 is a rear elevational view thereof, illustrated in the extended position;

FIG. 4 is a left-side elevational view thereof, illustrated in the extended position, the right-side elevational view being a mirror image thereof;

FIG. 5 is a top plan view thereof, illustrated in the extended position;

FIG. 6 is a bottom plan view thereof, illustrated in the extended position;

FIG. 7 is a perspective view of a collapsible canopy, illustrated in a collapsed position, showing the new design;

FIG. 8 is a front elevational view thereof, illustrated in the collapsed position;

FIG. 9 is a rear elevational view thereof, illustrated in the collapsed position;

FIG. 10 is a left-side elevational view thereof, illustrated in the collapsed position, the right-side elevational view being a mirror image thereof;

FIG. 11 is a top plan view thereof, illustrated in the collapsed position; and,

FIG. 12 is a bottom plan view thereof, illustrated in the collapsed position.

The broken lines showing a car seat in FIGS. 1 and 7, and the broken lines showing a flexible canopy fabric in FIGS. 1 and 4, are each included for the purpose of illustrating the invention in use, and form no part of the claimed design.
